UNITED STATES PATENT OFFICE.

THOMAS M. PETTY, OF OSWEGO, NEW YORK.

CHIMNEY-CLEANER.

SPECIFICATION forming part of Letters Patent No. 245,397, dated August 9, 1881.

Application filed December 29, 1880. (No model.)

To all whom it may concern:

Be it known that I, T. M. PETTY, of Oswego, in the county of Oswego and State of New York, have invented certain new and useful 5 Improvements in Manufacture of Lamp-Chimney Cleaners; and I do hereby declare the following to be a full, clear, and exact description of the invention, such as will enable others skilled in the art to which it pertains to 10 make and use it, reference being had to the accompanying drawings, which form part of this specification.

My invention relates to an improvement in the manufacture of chimney-cleaners; and it 15 consists, first, in the method of forming lamp-cleaners, consisting in wrapping the thread around the formers which are applied to the wire, partially twisting the wires, cutting the thread, and then twisting the wires, so as to 20 hold the thread in place and form the cleaner; second, in the combination of the bent wire into which the cut thread is twisted with two formers, which are applied to the wire, and around which the thread is twisted; third, in 25 the combination of the bent wire into or between which the thread is to be twisted with the two formers, one of which has a metallic plate secured to the center of its end, and which plate fits in a recess formed in the end of the 30 second former, for the purpose of forming, practically, one straight piece, when both formers are applied to the wire before it is bent; fourth, in the combination of the wire into which the thread is twisted, the two formers upon which 35 and the wire the thread is wrapped to form the sides of the cleaner, and a third former, which is applied to the bent end of the wire for the purpose of forming the end of the cleaner, all of which will be more fully described herein- 40 after.

Figure 1 is a side elevation of the bent wire and the two formers which are applied to its sides for the purpose of wrapping the thread around them. Fig. 2 shows the bent wire, having the former secured to its end. Fig. 3 shows the bent wire, having the two formers applied to it and the thread wrapped around them. Fig. 4 shows the cleaner complete.

A represents the wire upon which the cleaner 45 is formed, and which is bent double, as shown. Secured to the sides of the wire are the two

formers C, which are grooved down both of their sides, and have the shoulder D formed on their lower ends, for the purpose of serving as a guide to limit the length of the cleaner. 55 Secured in one end of one of these parts is a metallic plate, F, which projects into the end of the other guide, so as to hold the two pieces together, and thus form one continuous piece, upon which the large thick strands of the thread 60 are to be wrapped. After the strands of thread have been wrapped around both the wire and these formers in sufficient quantity the wire is bent double, as shown.

In order to make the end of the cleaner as 65 perfect as the sides, a third short former, O, is applied to the top of the wire, and around this former and bent portion of the wire is wrapped another thick strand of thread, which, when cut, is to form the end of the cleaner. This 70 former also acts as a lever to help in the twisting of the wire.

By means of the groove in the outer sides of the two vertical formers the strand of thread can be quickly and evenly cut after the wires 75 have been pressed tightly enough together to hold the thread in place, and then the wire is twisted so as to distribute the thread evenly over the whole surface of the cleaner in the usual manner. After the wire has been twisted 80 sufficiently to hold the cut thread securely in place the strand formed by the third former is cut, and this thread forms a thick cover for the end of the cleaner, so as to make it as soft and effective as any other portion. After the two 85 ends of the wire have been twisted sufficiently together they are inserted into any sort of a handle, I. The ends of the threads will be trimmed off, so as to be of one uniform length, either before or after the handle is applied to 90 the cleaner, and it is then ready for use.

By the use of thread made from cotton, flax, hemp, or any other fibrous material a very soft and perfect cleaner is produced, and which can be used for cleaning dishes and other such 95 articles equally as well.

Having thus described my invention, I claim—

1. In the manufacture of chimney-cleaners, the combination of the wire A with the formers C, having grooves in their inner edges for the wire to rest in and grooves in their outer

edges to facilitate the cutting of the strands, and provided with the shoulders D to limit the length of the cleaners, substantially as shown.

5 2. The method herein described of forming lamp-cleaners, consisting in wrapping thread around a wire and suitable formers, which are applied to the wire, cutting the thread, and then twisting the wire, so as to hold the cut 10 thread in position, substantially as described.

3. In the manufacture of lamp-cleaners, the combination of the wire with the two formers, around which and the wire the thread is wrapped, substantially as set forth.

15 4. The combination of the two formers C with the wire, one of the formers having a me-

tallic plate secured to its end, so as to project into the end of the other, and thus form one continuous piece, substantially as shown.

5. The combination, with the bent wire, of 20 the two formers C and the third former, which is applied to the bent portion of the wire, and around which the thread is wrapped, for the purpose of forming the end of the cleaner, substantially as set forth.

In testimony that I claim the foregoing I have hereunto set my hand this 20th day of December, 1880.

THOMAS M. PETTY.
